REGULATOR

Edward B. Foote, Rochester, N. Y., assignor to
 Taylor Instrument Companies, Rochester, N. Y.,
 a corporation of New York

Application December 18, 1934, Serial No. 758,088
 Renewed June 25, 1936

12 Claims. (Cl. 236—82)

This invention relates to regulating systems and more particularly to recording regulators.

The main feature of the invention relates to a regulating device, the sensitivity of which is universally adjustable over a wide range, the 5 adjustments being effected without disassembling any part of the mechanism.

Another feature of the invention relates to the construction of a recording regulator in 10 which the drag on the pen or stylus has been greatly reduced at all sensitivities and at certain sensitivities has been reduced to a negligible amount.

An additional feature relates to a regulating 15 device which can be readily changed from a "direct-acting" to a "reverse-acting" device, merely by rearranging certain of the parts of the operating mechanism and not by the addition of parts.

Still another feature of the invention relates to a simple regulating unit that can be used as a portion of a more complex instrument, in which the control point in the medium to be regulated is automatically changed or reset in accordance 20 with a change in a condition outside of said medium.

A further feature of the invention relates to improvements in direct ratio and inverse ratio reset regulating devices.

The various features and advantages of the 25 invention will appear from the detailed description and claims when taken with the drawings in which Fig. 1 is a plan view of the mechanism of a simple recording regulator of the present invention; Fig. 1a is a plan view of a plate which may be used in the device to change it from one 30 utilizing a sensitivity reducer to one that does not employ that principle of operation; Fig. 2 is a side elevation of a pillar construction for 35 mounting the pen arm brackets illustrated in Fig. 1; Fig. 3 is a fragmentary plan view of a portion of the structure shown in Fig. 1, illustrating how the device may be changed from a direct-acting to a reverse-acting regulator; Fig. 4 is a plan view of a recording regulator and a 40 diagrammatic showing of a portion of the regulating system in which it is incorporated; Fig. 5 is a somewhat enlarged plan view of the actuating mechanism of the regulator of Fig. 4; Fig. 45 6 is a cross-sectional view thereof taken substantially on the line 6—6 of Fig. 5 with a portion of the pillar construction; Fig. 7 is a side elevation of a portion of the structure shown in Fig. 5; Fig. 8 is a top view thereof partially in 50 section; and Fig. 9 is a fragmentary disclosure 55

of a portion of the construction illustrated in Fig. 5, showing how the direct ratio reset instrument there shown can have its parts rearranged to provide an inverse ratio reset regulator.

Referring especially to Fig. 1, 5 designates a 5 thermo-sensitive bulb which is connected by a capillary tube 6 to a Bourdon spring 7. The bulb 5, tube 6 and spring 7 constitute a tube system which may be filled with any suitable expansible medium, such as a liquid, a vapor or a combination of both. One end of the Bourdon spring is fastened by the spring mounting 8 to the frame of the instrument, while the free end of the spring is connected by a link 9 to the bracket 10 of a pen arm 11, which bracket has its staff 12 journaled in a suitable supporting column or pillar generally designated 13 (Fig. 2). The free end of the pen arm 11 is provided with a pen or stylus 14 which traces a curve corresponding to the changing temperature sensed by the medium 20 in the bulb 5, the curve being traced on a graduated chart 15 rotated in accordance with time 25 by a clock of which only arbor 16 is illustrated.

The staff 12 of the pen arm bracket is connected by a link 17 to the upper end of a baffle 25 actuating lever 18 which is provided with a pivot 19 at its lower end supported between the spaced arms of bracket 20, being held in position by the pivot screw 19a (Fig. 6). The lever 18 has mounted thereon, an adjustable, rotatable disc 30 21 provided with an eccentrically mounted stud 22 projecting toward the back of the instrument. The disc may be frictionally held in its adjusted position by suitable screws 21a also shown in Fig. 6. It will be understood that the rotation 35 of the disc 21 changes the adjustment of the stud 22 with respect to the baffle by a clockwise or a counterclockwise movement, as desired. A set lever 23 is likewise pivoted on the pivot stud 20a of bracket 20 beneath the lever 18, the pivot 40 stud and pivot 19 being in axial alignment. The upper end of this set lever is provided with teeth to form a sector gear 24 which is arranged to be driven by a gear train comprising gears 25, 25a and 25b. The square headed staff 26 of the gear 45 25 may be rotated by an adjusting key (not shown) to drive the mentioned gear train which actuates the sector gear 24 so that set lever 23 can be rotated clockwise or counterclockwise, as desired, about pivot stud 20a as an axis. A link 50 27 connects the upper end of the set lever to the staff 28a of the bracket 28 of a set point indicator S. This staff is rotatably mounted in the supporting column 13 as indicated in Fig. 2 with its axis in alignment with the axis of the staff 55

12 of the pen arm bracket. It will be understood that as the set lever 23 is rotated about the pivot stud 20a in response to the actuation of the train of gears, the set point indicator S will be moved 5 to indicate, in cooperation with the chart 15, the temperature that it is desired to maintain through the regulation by the present instrument.

On the lever 23 there is mounted for longitudinal movement a sliding plate 29 provided at 10 one side with a rack 30. This plate is limited to sliding movement by a pin 23a on the set lever which engages the edge of the plate opposite the rack and by a stud 34 (Fig. 6) mounted on the plate which stud engages the sides of slot 34a in 15 the set lever with a very close fit to prevent lost motion between the stud and the lever. A pinion 31, rotatively mounted on the set lever 23 opposite the pin 23a, engages the rack teeth formed on the plate 29 while the stub shaft 32 of 20 this pinion is slotted so that it may be rotated by means of a screw driver to move the plate 29 lengthwise to change the sensitivity of the instrument. By this construction the "unit sensitivity" 25 of the regulator can be readily adjusted or matched with respect to the time lag of the regulated process to afford steady action at the motor diaphragm valve. The term "unit sensitivity" as herein employed, is the distance of the control pen travel on the chart, necessary to cause a 10 30 lbs. air pressure change on the diaphragm motor valve V. In this description reference is made to a high and low unit sensitivity, "high sensitivity" being arbitrarily taken as the range of approximately $\frac{1}{64}$ " to approximately $\frac{3}{8}$ " pen 35 travel for a 10 lbs. air pressure change, and "low sensitivity" being arbitrarily taken as $\frac{1}{16}$ " to approximately 5" pen travel to effect a 10 lbs. pressure change. It is preferred to mount a graduated disc 33 on the shaft 32 for movement relative to an indicating mark 33a on the lever 23 40 to indicate different positions of sensitivity adjustment. The reduced end 35 (Fig. 6) of the stud 34 serves as a pivot for baffle 36. This baffle is provided with a right angular arm 37 having 45 at its free end a counterweight 38 so positioned that the upper end of the baffle normally tends to move counterclockwise toward the stud 22 and the lower end thereof tends to move toward a nozzle 39 to control the escape of pressure fluid. 50 The nozzle 39 is mounted on the face 40 of a flexible bellows or capsular diaphragm 41, the other face 42 of which is permanently mounted on a block 43 attached to the set lever 23. The orifice in the nozzle communicates through conduit 44 and the passage 45 in the block 43, with the conduit 46 which, in turn, communicates with a source of fluid pressure such as compressed air flowing through the constriction 46a. Conduit 46 also leads to the diaphragm 52 of the relay 55 valve 53. It will be noted that the block 43 is also connected by a branch conduit 47 communicating with the conduit 61 leading from the relay valve 53 to the diaphragm of the motor valve V, to be regulated. This block also has a passage-way 48 which communicates with a groove 49 in the plate 50 and thence through the passageway 51 to the capsular diaphragm 41. The diaphragm 41 thus serves as a "sensitivity reducer." Under certain conditions of regulation when a high 60 sensitivity adjustment is desired, the plate 50 is reversed end for end from its position, as shown, so that pressure fluid is prevented from flowing from the passageway 48 to the passage 51 and thence to capsular diaphragm 41 whereby this 65 diaphragm is thus rendered ineffective and con-

sequently no sensitivity reduction is effected thereby.

The instrument as shown in Fig. 1 is of the direct-acting type, that is, it operates on a rising temperature to cause the motor diaphragm valve 5 V to close. In the operation of the regulating system as disclosed in this figure, let it be assumed that the temperature about the bulb 5, rises and in consequence thereof it is desired to 10 close the diaphragm valve V which regulates the flow of steam through pipe 54 for heating the material about the bulb 5. In response to this increase in temperature, the filling medium within the bulb 5 expands, thereby causing the Bourdon spring 7 to unwind. As a result of this 15 unwinding movement, the link 9 moves the bracket 10 of the pen arm 11 clockwise, thereby moving the pen arm and its stylus to make a record of the temperature change on the chart 15. The pen arm bracket 10 and its staff move the 20 link 17 to swing the baffle-actuating lever 18 in a clockwise direction. If the temperature is now above the control point of the instrument, that is, the temperature indicated by the set point indicator S, the stud 22 on this lever swings the 25 baffle 36 clockwise about its pivot 35 with the result that the lower end of the baffle moves away from the nozzle 39. The pressure in the conduits 44 and 46 connected to the nozzle 39 thereupon 30 decreases causing the diaphragm 52 of the relay valve 53 to contract and to open this valve. The opening of this relay valve permits pressure fluid to flow through conduit 61 to the diaphragm of the motor valve V in the steam supply line 54, thus tending to close this motor valve. 35

In the event that the temperature about the bulb 5 falls, the filling medium therein will contract and the Bourdon spring 7 will tend to wind up. As a result of this movement, the link 9 moves the bracket 10 of the pen arm 11 counter-clockwise. The pen arm bracket 10 moves the link 17 to swing the baffle-actuating lever in a counter-clockwise direction. If the temperature about the bulb 5 is below the control point of the instrument, the stud 22 on the lever 18 recedes 45 from the baffle 36 permitting the counterweight 38 thereon to swing the baffle 36 counter-clockwise about its pivot 35 so that the lower end of the baffle moves toward the nozzle 39. The pressure in the conduits 44 and 46 connected to the 50 nozzle 39 increases, with the result that the diaphragm 52 and the relay valve 53 expands to close this valve. The closing of the relay valve cuts off pressure fluid to the conduit 51 leading to the diaphragm of the motor valve V in the 55 steam supply line 54 so that the motor valve tends to open.

The instrument as shown in Fig. 1 is arranged to have low sensitivity and as a result of this arrangement an increase in the flow of pressure fluid through conduit 61 to the motor valve V on a rise in temperature at bulb 5, increases the flow of pressure fluid in conduit 47, this pressure fluid, in turn, flowing through the passage 48, groove 49, passage 51, to the interior of the capsular diaphragm 41. The pressure fluid thus introduced into this diaphragm causes it to expand, with the result that the nozzle 39 follows gradually in the direction of the moving baffle 70 thereby causing the reduction in pressure of the fluid in conduit 46 to be more gradual and the operation of the relay valve 53 to take place more slowly so that the sensitivity of the instrument is reduced. Conversely, a drop in pressure in con- 75

duit 47 causes the nozzle to recede from the baffle.

In the event that it is desired to change the sensitivity adjustment of the instrument, the pinion 31 is rotated by a screw driver inserted in the kerf in the exposed end of the pinion shaft 32. The rotating pinion 31 meshes with the rack 30 on the plate 29 to raise or lower this plate, depending on the direction of rotation of this pinion. It will be noted that as the plate 29 is moved upward by a counterclockwise rotation of pinion 31 to increase the sensitivity of the instrument, the upper arm of the baffle 36, that is, the portion between the pivot 35 and the stud 22 is shortened, whereas the lower arm of the baffle between pivot 35 and the point where the baffle engages the orifice in the nozzle, is effectively lengthened. A clockwise rotation of pinion 31 reverses these conditions, that is, increases the length of the upper arm and decreases the length of the lower arm of the baffle, thereby reducing the sensitivity of the instrument. By this construction it is possible to have uniform progressive adjustment of the sensitivity of the instrument throughout a wide range of settings. It will be understood that as the sensitivity of the instrument is reduced, the upper arm of the baffle increases in length thereby reducing the effect of the counterweight 38 on the Bourdon spring 30 and consequently reducing the resulting motion of the pen 14, that is, the "pen drag".

If it is desired to change the set point of the indicator, a key (not shown) is applied to the square-headed staff 26 of the gear 25 of the train of gears, which gear train actuates sector gear 24 formed on the end of set lever 23 to swing this lever in either direction as desired. It will be recalled that the link 27 connects this plate to the bracket 28 of the set point indicator S so that as the lever is adjusted, this indicator is moved over the chart 15 to indicate the control temperature to which the instrument is being adjusted.

In Fig. 3 a fragment of the instrument is illustrated with its parts rearranged for reverse-acting operation. The arrangement of parts of this changed instrument is the same as that shown in Fig. 1, except that bracket 20 with the pivot stud 20a and pivot screw 19a, has been mounted in a different position on the frame. It will be noted that the pivot screw 19a now supports the pivot 19b (Fig. 6) mounted at an intermediate portion of the baffle actuating arm and the pivot stud 20a pivotally engages an intermediate portion of the set lever 23. In this arrangement all movements of the baffle are now reversed with respect to those previously described, so that a rising temperature at the bulb 5 will result in the operation of the relay valve 53 to shut off the pressure fluid flowing to the diaphragm motor valve V, thereby opening it. This is due to the fact that the baffle actuating lever 18 on a rising temperature will move the actuating stud 22 away from the baffle 36, instead of moving this stud toward the baffle as in the arrangement of Fig. 1. However, in the case of a falling temperature at the bulb 5, relay valve 53 will permit pressure fluid to flow to the motor valve V, causing it to close.

It should be understood that the instrument of Fig. 1 can be changed from the direct-acting to the reverse-acting type, or vice versa, merely by changing the mounting of bracket 20 so that the pivot points of the baffle actuating arm and

the set lever 23 are located at different positions as above described.

The mechanism disclosed in Fig. 1 is also particularly useful as a unit of a direct-ratio reset type of instrument in which one bulb or thermosensitive element 5 adjusts the control point or desired temperature to be maintained by the remainder of the instrument mechanism which includes a second thermosensitive element 75. For example, in certain installations it is desirable to control the temperature in a room in a certain predetermined relation with respect to the temperature prevailing outside of this room, as for instance when the outside temperature is hot it may be desirable to raise the control point of the instrument to maintain the temperature within the room at a somewhat higher value, whereas when the outside temperature is cold it may be desirable to lower the control point of the instrument to maintain the temperature within the room at a lower value. The term "ratio" means the magnitude of the change of the setting temperature (at bulb 75), as compared to that of the controlled temperature at bulb 5. The expression "direct ratio" is used to convey the idea that the controlled temperature changes in the same sense as the setting temperature.

Such a reset instrument is disclosed in Figs. 4 to 8 wherein there is illustrated a thermosensitive bulb 5, capillary tube 6 and a Bourdon spring 7 similar to that already described. It will be understood that this bulb is to be placed in the room or compartment wherein the temperature is to be regulated. The free end of the Bourdon spring 7 is connected by a link 9 to the bracket 10 of the pen arm 11 which bracket has its staff 12 pivoted in the column 13 of Figs. 2 and 6. In the present instance the pen arm bracket has attached thereto an arm 70 (Fig. 5), the lower end of this arm being connected by a link 71 to the lower end of lever 72 which is pivoted at 73 on a swingable arm 83 movable about the pivot 14. The upper end of the lever 72 is connected by a link 77 to the baffle-actuating lever 18. The mounting of the baffle-actuating lever together with the mounting of the baffle and the nozzle are identical with the arrangement disclosed in Fig. 1 and need not be further described herein.

The bulb 75 of a second fluid-filled thermosensitive unit is located outside of the room or compartment where the temperature is to be regulated. This thermosensitive unit serves to reset automatically the control point of the instrument to maintain a predetermined relation between the regulated condition at bulb 5 and the prevailing condition at the bulb 75, instead of utilizing the manual adjustment of the set point lever 23 to change the control point and also the position of the set point indicator S as in the instrument of Fig. 1. On this reset type of instrument, the manual adjustment including the gear train 25, is utilized to change the point of control independently of the automatic reset. The bulb 75 communicates through a capillary tube 76 with a Bourdon spring 77, the fixed end 78 of which spring is mounted at 78 on the frame of the instrument. The free end of the Bourdon spring is connected by a link 79 to the bracket of a second pen arm 80, likewise mounted on a pivot with its axis in alignment with the axis of the staff 12. As best shown in Fig. 5, the bracket of the pen arm 80 (Fig. 4) is provided with an extension 81 (Fig. 6). This extension at an intermediate point thereon is pivotally connected by a link 82 to the swingable arm 83, 75

which it will be recalled is pivoted at 74 and which carries the fulcrum 73 for the portion of the linkage that actuates the baffle-actuating arm 18.

- 5 The operation of the reset regulator is as follows: If the temperature at the bulb 5 rises, the filling medium in the tube system expands causing the Bourdon spring 7 to unwind. The link 9 connected thereto is thus moved toward the left causing the pen arm bracket 10 and its attached arm 70 to swing in a clockwise direction. The link 71 is connected to the lower end of the arm 70 and lever 72 so that the swinging movement of this arm 70 effects a corresponding clockwise swinging movement of lever 72 about the pivot 73. The swinging movement of the lever 72 which has its upper end connected by link 17 to the upper portion of the baffle-actuating lever 18, causes a corresponding swinging movement of the lever 18 so that the baffle 36 is moved away a corresponding amount from the nozzle 39. The effect of the varying relation between the nozzle and the baffle on the valve V is the same as that described in connection with the instrument of Fig. 1 and need not be further described. A drop in temperature about the bulb 5 effects a similar operation of the parts of the instrument, but in the reverse sense.

If the temperature about the bulb 75 rises, the filling medium therein will cause the Bourdon spring 77 (Fig. 4) to unwind. This motion of the spring 77 causes the link 79 to swing the bracket of pen arm 80 in a clockwise direction. Link 82 connecting this bracket and arm 83 is actuated by this bracket to swing arm 83 in a counter-clockwise direction to move the pivot 73 on which lever 72 is mounted, toward the left. Such a movement causes lever 72 to turn clockwise about pivot 73a (Fig. 5), thus imparting movement to link 17 and lever 18 so that baffle 36 is moved nearer to the nozzle 39. As a result of this relative movement of the baffle and nozzle, valve V opens as described in connection with Fig. 1, increasing the temperature at bulb 5 and causing Bourdon spring 7 to unwind. This movement is transmitted to baffle 36 as described but in the opposite direction from that caused by Bourdon spring 77, thus restoring the baffle and nozzle to a control relation but at a higher temperature equivalent.

In order to change the ratio adjustment of the direct ratio reset instrument, the parts 81a and 83a are moved along their respective levers 81 and 83, thus changing the distance between pivots 74 and 74b.

In the fragmentary view of Fig. 9 certain of the parts of the direct ratio reset instrument of Figs. 4 to 8 have been rearranged to change that instrument into one of the inverse ratio reset type. The expression "inverse ratio" is used to mean that the controlled temperature changes in the opposite sense from the setting temperature. In this rearranged instrument the bracket plate 84 and the pivot 74 carried thereby are mounted in a different position in the case (not shown in this figure), the pivot 74 and its supporting plate being disconnected from the lower end of arm 83. Also the pivot clip support 83a and the arm section 81a with link 82 are removed from intermediate portions of arms 83 and 81 and are then attached respectively to the lower ends of these arms so that these ends will be connected by link 82.

The operation of this inverse ratio reset instrument is similar to that of the direct ratio

type except that on a rise in temperature at bulb 75 the pivot 73 is moved toward the right so that the control point is lowered. In other words, as the temperature rises at bulb 75, bulb 5 maintains the controlled temperature at a lower value. On a drop in temperature at bulb 75, the pivot 73 is moved toward the left so that the control point is raised and the controlled temperature is maintained at a higher value.

To change the ratio adjustment of the inverse ratio reset instrument, bracket 84 carrying pivot 74 is moved along lever 83 thus changing the distances between pivot 74 and the end pivots 73 and 74c.

While the present instrument has been described with particular reference to the regulation of temperature, it is equally applicable to the regulation of pressure, flow, liquid level and like variable conditions.

I claim:

1. In a regulating system, a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a movable baffle cooperating with said orifice, mechanism including an element responsive to variations in said condition and operatively associated with said baffle to vary the relation of the same with respect to said orifice in accordance with said variations, and single means for adjusting by small increments of movement over a wide range of adjustment the position of said baffle to change the effective length thereof with respect to said orifice, and with respect to said mechanism.

2. In a regulating system, a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a pivoted baffle cooperating with said orifice, a flexible bellows on which said nozzle is mounted, said bellows being actuated by the controlled pressure fluid applied to said motor, an element responsive to variations in said condition and operatively associated with said baffle to vary the relation of the same with respect to said orifice in accordance with said variations, and means for adjusting said baffle to change the effective length thereof with respect to said orifice by small increments of movement over a wide range of adjustment.

3. In a regulating system, a pressure fluid operated motor valve arranged to control the flow of a regulating medium to maintain a predetermined condition, means for controlling the supply of pressure fluid to the motor of said valve and the discharging of fluid therefrom, said means including a nozzle having an orifice and a baffle cooperating with said orifice, said nozzle and said baffle being carried by a common adjustable support, an element actuated in response to variations in said condition and engaging said baffle to vary the relation of the same with respect to said orifice in accordance with said variations, means including a reduction gear train for adjusting said support with respect to said element to establish a new predetermined condition, and means for changing the effective length of said baffle with respect to said orifice.

by small increments of movement over a wide range of adjustment.

4. In a regulating system, a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a movable baffle cooperating with said orifice, a movable arm provided with a part engaging said baffle, means responsive to variations in said condition and operating said arm to control said baffle to vary the relation of the same with respect to said orifice in accordance with said variations, and single means for changing the effective length of said baffle with respect to said orifice and with respect to said part by small increments of movement over a wide range of adjustment.

5. In a regulating system, a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a baffle cooperating with said orifice, a movable arm provided with a projection engaging said baffle, said baffle being pivoted between said projection and said nozzle to define two baffle arms, means responsive to variations in said condition for operating said arm and projection to control said baffle in order to change the relation of the same with respect to said orifice in accordance with said variations, and single means for proportionally varying the lengths of said baffle arms by small increments of movement.

6. In a regulating system, a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a pivoted baffle cooperating with said orifice, a counter-weight supported on an arm projecting from said baffle adjacent the pivot whereby said baffle tends to swing with respect to said nozzle, a movable arm provided with a projection engaging said baffle, said baffle being pivoted between said projection and said nozzle to define two baffle arms, means responsive to variations in said condition and operating said arm and projection to control said baffle in order to change the relation of the same with respect to said orifice in accordance with said variations, and single means for proportionally varying the effective lengths of said baffle arms by small increments of movement.

7. In a regulating system a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a baffle cooperating with said orifice, a movable arm provided with a part engaging said baffle, a pivot on said arm at each side of said part, a pivot support transferable from one pivot to the other to change the regulation effected by said system from direct action to reverse action, means responsive to variations in said condition and operating said arm and part to control said baffle in order to change the relation of the same with

respect to said orifice in accordance with said variations, and means for changing the effective length of said baffle with respect to said orifice by small increments of movement over a wide range of adjustment.

8. In a regulating system, a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a baffle cooperating with said orifice, a movable arm provided with a part engaging said baffle, said arm being arranged to be pivotally mounted at either of two points thereon at opposite sides of said part, pivotal mounting means for said arm transferable from one of said points to the other to change the regulation effected by said system from direct action to reverse action, means responsive to variations in said condition and operating said arm and part to control said baffle in order to change the relation of the same with respect to said orifice in accordance with said variations, and means for changing the effective length of said baffle with respect to said orifice by small increments of movement over a wide range of adjustment.

9. In a regulating system, a pressure fluid operated motor valve arranged to control the flow of a regulating medium to maintain a predetermined condition, means for controlling the supply of pressure fluid to the motor of said valve and the discharge of fluid therefrom, said means including a nozzle having an orifice and a baffle cooperating with said orifice, a baffle supporting lever arranged to be pivotally mounted at either of two spaced points thereon, a movable arm provided with a part engaging said baffle, said arm being arranged to be pivotally mounted at either of two points thereon at opposite sides of said part, pivotal mounting means for said lever and said arm transferable from one pair of points to the other pair to change the regulation effected by said system from direct action to reverse action, means responsive to variations in said condition and operating said arm and part to control said baffle in order to change the relation of the same with respect to said orifice in accordance with said variations, and means for changing the effective length of said baffle with respect to said orifice by small increments of movement over a wide range of adjustment.

10. In a regulating system, a pressure fluid operated motor valve arranged to control the flow of a regulating medium to maintain a first condition in a definite relation to a second condition, means for controlling the supply of pressure fluid to the motor of said valve and the discharge of fluid therefrom, said means including a nozzle having an orifice and a movable baffle cooperating with said orifice, means responsive to variations in said first condition and to variations in said second condition, said means being operatively associated with said baffle to vary the relation of the same with respect to said orifice in accordance with said variations, and mechanism for adjusting by small increments of movement over a wide range of adjustment, the position of said baffle to change the effective length thereof with respect to said orifice.

11. In a regulating system, a pressure fluid operated motor valve arranged to control the flow of a regulating medium to maintain a first condition in a definite relation to a second condition, means for controlling the supply of pressure fluid

- to the motor of said valve and the discharge of fluid therefrom, said means including a nozzle having an orifice and a movable baffle cooperating with said orifice, means responsive to variations 5 in said first condition and to variations in said second condition, said means being operatively associated with said baffle to vary the relation of the same with respect to said orifice in accordance with a direct ratio between said variations 10 jointly, and mechanism for adjusting by small increments of movement over a wide range of adjustment, the position of said baffle to change the effective length thereof with respect to said orifice.
- 15 12. In a regulating system, a pressure fluid operated motor valve arranged to control the flow of a regulating medium to maintain a first con-

dition in a definite relation to a second condition, means for controlling the supply of pressure fluid to the motor of said valve and the discharge of fluid therefrom, said means including a nozzle having an orifice and a movable baffle cooperating 5 with said orifice, means responsive to variations in said first condition and to variations in said second condition, said means being operatively associated with said baffle to vary the relation of the same with respect to said orifice in accordance 10 with an inverse ratio between said variations jointly, and mechanism for adjusting by small increments of movement over a wide range of adjustment, the position of said baffle to change the effective length thereof with respect 15 to said orifice.

EDWARD B. FOOTE.
